UNITED STATES PATENT OFFICE

130,941

DESIGN FOR SLIP-OVER EYEGLASSES

Amelita J. Crealese, Chicago, Ill.

Application October 4, 1941, Serial No. 103,638

Term of patent 14 years

To all whom it may concern:

Be it known that I, Amelita J. Crealese, a citizen of the United States, residing at Chicago, in the county of Cook and State of Illinois, have invented a new, original, and ornamental Design for Slip-over Eyeglasses, of which the following is a specification, reference being had to the accompanying drawing, forming a part thereof.

In the drawing:

Figure 1 is a front elevational view of a pair of slip-over eyeglasses embodying my new de-

sign, said glasses being shown in the position which they assume when attached to a supporting pair of glasses.

Figure 2 is a rear elevational view of my slip-over glasses as they appear when detached from the supporting structure.

Figure 3 is a top plan or edge view of the glasses shown in Figure 2.

I claim:

The ornamental design for slip-over eyeglasses, substantially as shown and described.

AMELITA J. CREALESSE.
